UNITED STATES PATENT OFFICE.

JEROME I. VOGELER, OF BALTIMORE, MARYLAND.

ADVERTISING BOTTLE OR FLASK.

SPECIFICATION forming part of Letters Patent No. 716,793, dated December 23, 1902.

Application filed June 23, 1902. Serial No. 112,761. (No model.)

To all whom it may concern:

Be it known that I, JEROME I. VOGELER, of the city of Baltimore, State of Maryland, have invented certain Improvements in Advertising Bottles or Flasks, of which the following is a specification.

This invention is based on the well-known property of the cylindrical mirror to produce two entirely different effects by a change in its position—that is to say, when the axis of the mirror is vertical the image reflected is elongated vertically and when it is horizontal the image is extended horizontally or widened. To adapt this peculiarity of the cylindrical mirror to an advertising bottle or flask, I combine with the mirror the phrases "Before taking" and "After taking," the former being so situated with reference to the mirror that when it is readable the reflection of the face of the person looking in the mirror is elongated vertically and produces an effect which is popularly supposed to indicate distress. The latter phrase is so situated with reference to the mirror that when it is readable the reflected face is broadened, so as to indicate mirth or satisfaction, the scheme of the advertising device being to illustrate the difference in the appearance of a person before and after taking a beverage.

In the drawings forming a part hereof, Figure 1 is a front or face view of the advertising bottle or flask, and Fig. 2 a central cross-section of the same.

Referring now to the drawings, A is a bottle or flask having at one side thereof a sunken panel B, whose surface is a segment of a circle with the axial line extending in the direc-

tion of the length or height of the flask. Within this sunken panel and secured to its segmental surface is a mirror C, consisting 40 of a segmental plate of silvered glass. At the four sides of the mirror are the smaller sunken panels D, E, F, and G. In the panels E and D, which are respectively at the top and to the left of the mirror, are secured the 45 plates a and b. The plate a contains the phrase "Before taking" and the one b the phrase "After taking." The other panels F and G are for the name of the beverage contained in the flask; but these are left blank 50 in the drawings.

The flask when presented to a person who is invited to partake of its contents is held in a vertical position and the recipient sees his face elongated and reads the words "Before taking." Afterward the flask is turned to the right, so that the recipient will see his face broadened and will read the words "After taking."

I claim as my invention—

An advertising-flask having at one side thereof, a sunken panel the surface of which is a segment of a cylinder, the axial line of the segment being in the direction of the length of the flask, combined with a cylindrical mirror having an inner surface which corresponds in shape with that of the panel to which it is secured, substantially as, and for the purpose specified.

JEROME I. VOGELER.
